BOX AND METHOD OF MAKING SAME

Application filed January 12, 1923, Serial No. 612,170. Renewed September 24, 1926.

My invention relates to methods of producing box blanks and boxes, conveniently described as continuous production methods, in general conformity with previous box structures and methods of my invention, and also in general conformity with companion applications, executed on even date herewith.

The present application relates more particularly to the box end formation, and especially to the provision of a smooth and attractive box end finish in which every portion of the box shell or body material, including all edges, is covered and concealed by portions of the overlying cover paper, with the exception that in one variation of the method and structure which is preferred in some cases, thin side edges of the shell end wings are slightly, (more or less) exposed by reason of the fact that the adjacent edges of the cover paper are cut off flush with these shell edges in the formation of the blanks.

Incidental to the provision of a completely or approximately completely "finished", smooth and attractive end structure, referred to above, the invention includes process steps for reducing the thickness of marginal portions of the shell end wings, these operations being conveniently described as "skiving" operations, properly co-ordinated with other operations of my continuous production method.

Various forms of boxes are here shown and described in order that the processes of production may be fully understood; but the blanks and boxes per se are disclosed and claimed in a divisional application.

The characteristics and advantages of the invention are further sufficiently described in connection with a detail description of the accompanying drawings, which explain certain representative performances of the process or method. After considering these examples, persons skilled in the art will understand that many variations may be made within the principles of the invention, and I contemplate the employment of any methods and structures which are properly within the scope of the appended claims.

Figure 1 is a perspective view sufficiently

illustrating the process in one form, up to the point where the individual blanks are severed.

Figure 2 is a detail view explaining the skiving operation.

Figure 3 is an enlarged fragmentary section of the shell web at a point subsequent to the routing and skiving operations. 55

Figure 4 is a detail view in section, showing a slitting operation.

Figure 5 is a perspective view of a severed "individual" blank. 60

Figure 6 is a perspective view of one end of a completed box produced from the blank, Fig. 5, with end and side portions in section. 65

Figure 7 is an enlarged horizontal section through the completed box at one corner.

Figure 8 is a perspective view illustrating a modification of the processes.

Figure 9 is a bottom plan of the materials in the course of operations in conformity with Fig. 8 from the point of cover assembly contact to the point of individual blank cut-off. 70

Figure 10 is an enlarged sectional detail of the shell web after the routing and skiving operations. 75

Figure 11 is an enlarged detail section at 11-11, Fig. 12, of the assembled materials after the operation of punching to separate end wing and corner lap portions.

Figure 12 is a perspective view of an individual severed blank. 80

Figure 13 shows the blank partly folded into box form.

Figure 14 is a perspective view of the completed box part. 85

Figure 15 is a perspective view of one corner of the completed box with side and end wall portions sectioned.

Figure 16 is an enlarged section in a horizontal plane of one corner of the completed box. 90

Figure 17 is a plan view of one end of a complete box blank showing a style of embossing.

Figure 18 is a section of the same. 95

In the process as exemplified in Fig. 1 a continuous strip or web of suitable box body or shell material 1 is advanced from a roll 2 and at a suitable point longitudinal fold lines 3 are produced in any suitable way. Part 100

ticularly in the present example these longitudinal fold lines are channels of substantially rectangular cross section produced by grinding wheels 4 driven usually at high speed in contact with the web, and this method of producing longitudinal fold lines may be conveniently described as "routing." Subsequently at regular intervals the shell material is reduced in thickness by any suitable means 5 on substantially rectangular areas extending inward from the longitudinal fold lines. This operation is conveniently described as "skiving" and may be performed by grinding wheels 5 driven at suitable speed and 10 arranged on oscillating carriers 6 which may be operated at proper intervals by mechanism such as cam mechanism 7 to bring the wheels in contact with the advancing web and produce the skived or beveled areas 8. This operation, however performed, is for the purpose of reducing the thickness of the shell material along certain edges which are subsequently produced by cutting or punching operations, and most desirably the cutting or 15 removal of material is on an angular or beveled plane in the transverse direction of the blank, so as to gradually reduce the thickness of the material in outward directions. The formation of the shell web including the longitudinal fold channels 3 and the skived or 20 beveled areas 8, is most clearly shown in Fig. 3.

In order to provide for free or projecting cover end wing margins in one particular 25 form of box, central rectangular openings 10 are cut or punched in the shell material, these openings usually extending all the way from one longitudinal fold line to the other, and concurrently, or otherwise before or after the 30 openings 10 are punched, longitudinal slots 11 are produced in the blank, these being usually commensurate with the width of the fold lines and of a suitable length extending in both directions from the central openings 40 10 to correspond to the desired end wing length of the completed box-blank. By this operation thin longitudinal free edges 12 are produced in the shell material at the inner sides of the slots 11.

50 In the further advance of the shell material transverse fold lines 14 are produced, and desirably these are relatively deep gathered folds in the production of which the shell material is more or less broken down so that it will fold properly with the applied cover material without unduly straining or breaking the cover material when the individual blanks are folded. In some cases these transverse fold lines may be formed 55 after the cover material is applied, and in general it is to be understood that the order of operations may be varied considerably, and there is no limitation as to the order of operations except in cases where the particular 60 operation must necessarily or most ad-

vantageously be performed after the performance of another or other operations. For example, the operations of routing, skiving and punching may be varied in their order to a considerable extent although the 70 order of operations above described is the most convenient and desirable in many cases.

A continuous strip or web of suitable cover paper 15 is advanced from a roll 16, and desirably during its advance toward the point of contact with the shell web this paper is suitably treated to provide upon its desired indicia or designs, and in the present specific example this treatment of the cover paper consists in embossing it. For this purpose 80 the cover web is passed between co-operating embossing rolls 17 and 18, carrying suitable embossing dies or surface conformations 19 to produce a suitable embossed design 20 upon the cover paper, and this may be in a 85 particular example a panel of suitable indicia or decorative subject matter to be located on a stated area of the completed box part, such as the "top" or "bottom" area of the box part, or one of the end or side panels, 90 or otherwise the embossed design may extend more or less over the entire surface of the cover paper, one suitable all-over embossed design being sufficiently exemplified in Figures 17 and 18.

95 The cover web is then passed over a glue roll 21 and is then brought in contact with the shell web and pressed thereon, an upper pressing roll 22 being shown for this purpose in Fig. 2, this roll of course co-operating with 100 a lower pressing roll, which is omitted for the sake of clearness. Desirably the cover web is of such width that it has margins 24 projecting beyond the edges of the shell web, and these margins are folded over and 105 pressed on under marginal surfaces of the shell web by pressing rolls 26 and 27. Glued cover paper then overlies the apertures 10 and 11 previously produced in the same web.

110 In the further advance of the assembled material slits 28 are formed in the cover paper approximately centrally of the shell slots 11, and these slits are of substantially the same length as the slots. The slitting operations may be performed by rotary slitting wheels 30 as best explained in Fig. 4. These slitting operations are for the purpose of severing the cover paper to divide the cover corner laps from the cover end wings. In the further advance of the continuous 115 assembly, portions are cut from it at regular intervals along the straight transverse lines 35, Fig. 1, producing individual blank assemblies B, Fig. 5, each consisting of combined shell and cover material and including a central or body portion *a*, side wings *b*, corner laps *c* extending from the ends of the side wings, and shell end wings *d* having skived or beveled marginal portions 8 with the thin edges 12 produced in the manner previously 120 125 130

described. The blank also includes cover end wing end margins *e* extending beyond the ends of the shell end wings and narrow cover margins *f* projecting alongside the thin shell edges 12, these cover margins *e* and *f* being supplied with adhesive which remains fresh or tacky during the rapidly performed process operations, and the blank also usually includes narrow cover marginal portions *g* at the opposite sides of the slits 28 to the marginal portions *f*, these margins *g* extending alongside the inward edges *h* of the shell corner laps. The cover margins *g* are usually immaterial or superfluous but they are usually produced as an incident to the production of the desired margins *f*. The width of the margins *g* may be reduced to practically any desired extent or they may be substantially eliminated by making the slits 28 as close as is convenient or desirable to the shell edges *h*. The margins *g*, however, when produced in the manner described, are unobjectionable and in the completed box they lie along central portions of the transverse fold lines or creases 14 and are more or less, or entirely concealed from view.

The blank is now folded into box form by any suitable number of intermediate operations or steps as sufficiently indicated in Fig. 13 in which the same style of box is produced with the exception of a slight difference in the end wing side edge formation. In the folding process the side wings *b* are turned up, the corner laps *c* are turned in, the end wings *d* are turned up against the outer surfaces of the corner laps, and finally the projecting cover margins *e*, coated with adhesive as above described, are turned in and pressed against inward margins of the corner laps and the adhesively coated narrow cover margins *f* are pressed down and adhesively secured to outer surfaces of the corner laps along the vertical corners of the box, Fig. 6, completely covering and concealing the thin skived shell edges 12. The sloping or graduated skiving or beveling of the shell margins adjacent to the edges 12 moreover provides for a substantially smooth and unbroken outer box end surface. The adhesive application of the cover margins in the described manner is sufficient in many cases to retain the box end structure in permanent form, but when necessary or desirable additional adhesive may be supplied to the outer surfaces of the corner laps *c* or to the inner surfaces of the shell end wings *d*, and this adhesive application may be made at any convenient point in the process operations either before the materials are severed from the continuous web or after severing.

In the preceding example of the process a great many of the operations, and all of the operations performed upon the shell material, were performed previous to assembly contact, and especially the narrow strips of

material to form the longitudinal slots 11, were cut from the shell before its assembly contact with the cover web.

Figures 8 to 16 inclusive, illustrate a variation in the process in which the punching or cutting operations to remove the longitudinal strips are performed after assembly contact, and therefore, are necessarily performed upon the combined materials, and these figures also illustrate other variations consisting in the formation of transverse fold lines or creases after assembly contact so that the crimping or pressing operations which form the creases are formed on the cover material along with the shell material.

In this performance of the process the shell web 1 is advanced and the longitudinal fold lines in the form of channels 3 are produced by routers 4, and at a suitable point skiving wheels 5 produce beveled or skived surfaces 40, Figures 8 and 10, the beveled surfaces 40 merging in a transverse direction of the blank into the surfaces 41 which constitute the bottoms of the folding channels. In the further advance of the web, central portions are cut or punched out to form openings 10, as in the previous example, but longitudinal slotting of the material along the fold lines is omitted. The cover web 15 is then applied in the same manner as previously, and the margins are folded over and secured. Thereafter transverse fold lines or creases 45 are produced and at a suitable point in the further advance of the combined materials narrow strips of material are cut out to provide longitudinal slots 50, and since these cuts are made after the cover paper is associated with the shell web, both of these materials are severed, leaving narrow edges 51 and 52 of the shell and cover materials, respectively, exposed along the inner edges of the slots. The blank is then severed by transverse cutting as previously shown producing individual blank assemblies B', Fig. 12, which may be substantially identical with the previous blank assembly except for the formations adjacent to the slots 50. The blank is folded into box form by any suitable number of intermediate operations or stages, as sufficiently explained in Fig. 13, with or without the supply of additional adhesive as explained in connection with the previous example, producing the completed box as shown in Figures 14, 15 and 16, having all the characteristics of the previously described structure including completely covered exterior surfaces and shell edges, and with margins of the cover paper applied all around the inner margins of the side and end walls, except, as a significant difference from the previous structure, the thin edges 51 of the shell end wings are slightly, (more or less) exposed. The skiving operation may be performed so as to make the material along these edges as thin as may be practicable or

desirable; in other words, the exposed edge 51 may be so thin that it is practically unnoticeable and indistinguishable from the adjacent superposed edge of the cover material, or otherwise when it is not practicable to skive the material so deeply, this edge may be somewhat thicker and more noticeable and this exposure of the edge of the cover material of moderate thickness is unobjectionable in many classes of boxes.

In this particular form of the invention it is usually desirable to supply adhesive at least along the skived surfaces of the shell, or on surfaces of the corner laps which will correspond to these skived surfaces when applied. The roughened, skived surfaces of the shell material readily adhere to the corner laps and these surfaces, and especially their edges, are easily pressed down and held in secure engagement so that the edge finish of the box is very secure and durable.

The embossing operation previously described may be carried out in connection with the process as shown in Figures 8 to 16, or the embossing may be omitted, in accordance with requirements.

Figures 17 and 18 illustrate one form of "all-over" embossing, wherein a mottled or "pebbled" appearance is imparted to the cover paper 15^a, by suitable embossing rollers as in Figure 1. When such an "all-over" embossed design is produced upon the cover material, it is important in the subsequent creasing or folding operations, to avoid injuring the embossed finish, and for that reason the transverse creases 14 are desirably formed in the shell material before assembly contact, as in Figure 1, without any necessity for creasing the combined materials including the cover paper, which would injure or alter the appearance of the embossed paper along the creased lines.

I claim:

1. A method of producing box blank assemblies comprising associating and securing a continuous web of cover material and a continuous web of shell material in facial contact, producing longitudinal fold lines in the shell web, reducing the thickness of the shell web at intervals adjacent to the longitudinal fold lines, and severing the combined materials transversely at regular intervals, to produce individual box-blanks.

2. A method of producing box blank assemblies, comprising associating a continuous web of cover material and a continuous web of shell material in facial contact with interposed adhesive, producing longitudinal fold lines in the shell web, reducing the thickness of portions of the shell web at intervals adjacent to the longitudinal fold lines, producing individual blank formations in the continuous materials including severing them transversely at regular intervals to produce individual blanks having end wing

portions including cover material and shell material with margins of reduced thickness produced in the thickness-reducing operation above mentioned.

3. A method of producing box blank assemblies comprising associating a continuous web of cover material and a continuous web of shell material in facial contact with interposed adhesive, producing longitudinal fold channels in the shell web, skiving the shell on one side to reduce the thickness of portions of the shell web at intervals adjacent to the longitudinal fold lines, and producing individual blank formations in the continuous materials including severing them transversely at regular intervals to produce individual blanks having end wing portions including cover material and shell material with margins of reduced thickness produced in the thickness-reducing operation above mentioned.

4. A method of producing boxes, comprising associating and securing a continuous web of cover material and a continuous web of shell material in facial contact, producing longitudinal fold lines in the shell web, reducing the thickness of the shell web at intervals adjacent to the longitudinal fold lines, severing the combined material transversely at regular intervals, to produce individual box-blanks, and folding the blanks into box form with shell-wing portions of reduced thickness adhesively secured along outer surfaces of the box end structure to produce a substantially smooth exterior box end finish.

5. A method of producing boxes, comprising associating a continuous web of cover material and a continuous web of shell material in facial contact with interposed adhesive, producing longitudinal fold lines in the shell web, reducing the thickness of portions of the shell web at intervals adjacent to the longitudinal fold lines, producing individual blank formations in the continuous materials including severing them transversely at regular intervals to produce individual blanks having end wing portions including cover material and shell material with margins of reduced thickness produced in the thickness-reducing operation above mentioned, and folding the blanks into box form with the shell-end-wing portions of reduced thickness adhesively secured along outer surfaces of the box end structure to produce a substantially smooth exterior cover end finish.

6. A method of producing boxes, comprising associating a continuous web of cover material and a continuous web of shell material in facial contact with interposed adhesive, producing longitudinal fold channels in the shell web, skiving the shell on one side to reduce the thickness of portions of the shell web at intervals adjacent to the longitudinal fold lines, producing individual blank formations in the continuous materials including sever-

ing them transversely at regular intervals to produce individual blanks having end wing portions including cover material and shell material with margins of reduced thickness produced in the thickness reducing operation above mentioned, and folding the blank into box form with the shell-end-wing portions of reduced thickness adhesively secured along outer surfaces of the box end structure 10 to produce a substantially smooth exterior cover end finish.

7. A continuous box blank production method including the steps of advancing a continuous web of shell material, producing longitudinal fold lines therein, removing portions of the shell material at intervals adjacent to the longitudinal fold lines to produce sloping or beveled end wing margins of individual blanks, adhesively applying a continuous web of cover material to the shell web, forming transverse fold lines, cutting the cover material longitudinally adjacent the shell portions of reduced thickness above mentioned, and severing the combined materials at regular intervals to produce individual blank assemblies.

8. A continuous box blank production method comprising advancing a continuous web of shell material, routing out the shell material on one face in parallel lines to produce longitudinal fold channels, cutting out sections of the shell material between the fold channels at intervals, cutting narrow longitudinal strips from the shell material substantially in line with the longitudinal channels, beveling marginal portions of the shell material adjacent to the aforesaid cut-out locations, applying a continuous web of adhesively coated cover material to a surface 40 of the shell web, slitting the cover material along lines substantially corresponding to the cut-out strips above mentioned, and severing the continuous assembly at regular intervals to produce individual blanks.

45 9. A continuous box blank production method comprising advancing a continuous web of shell material, forming longitudinal fold lines therein, skiving the shell material at intervals adjacent to the fold lines, forming apertures in the shell material in substantially centered relation to the skived areas, forming narrow longitudinal slots in the shell web substantially co-extensive with the fold lines and of substantially the same 55 length as the skived areas, advancing a continuous web of cover material and applying it adhesively to a surface of the shell web, slitting the cover material on lines substantially corresponding to the longitudinal slots 60 above mentioned, forming transverse fold lines, and cutting off the combined materials at regular intervals to produce individual box blanks.

10. A continuous box blank production 95 method comprising the steps of associating

a continuous web of shell material and a continuous web of cover material in facial contact with interposed adhesive, pressing the materials to produce longitudinal and transverse fold lines, producing skived areas on an outward face of the shell material adjacent to the longitudinal fold lines and narrow longitudinal slots alongside the skived areas whereby thin free edges of the shell material are produced corresponding to edges of the shell end wings in the completed blank assemblies; and severing the combined materials transversely at regular intervals to produce the individual assemblies.

11. A continuous box production method including the steps of advancing a continuous web of shell material, producing longitudinal fold lines therein, removing portions of the shell material at intervals adjacent to the longitudinal fold lines to produce sloping or beveled end wing margins of individual blanks, adhesively applying a continuous web of cover material to the shell web, forming transverse fold lines, cutting the cover material longitudinally adjacent to the shell portions of reduced thickness above mentioned, severing the combined materials at regular intervals to produce individual blank assemblies, and folding and securing the individual blanks in box form.

12. A continuous box production method comprising advancing a continuous web of shell material, routing out the shell material on one face in parallel lines to produce longitudinal fold channels, cutting out sections of the shell material between the fold channels at intervals, cutting narrow longitudinal strips from the shell material substantially in line with the longitudinal channels, beveling marginal portions of the shell material adjacent to the aforesaid cut-out locations, applying a continuous web of adhesively coated cover material to a surface of the shell web, slitting the cover material along lines substantially corresponding to the cut-out strips above mentioned, severing the continuous assembly at regular intervals to produce individual blanks, and folding and securing the individual blanks in box form.

13. A continuous box production method comprising advancing a continuous web of shell material, forming longitudinal fold lines therein, skiving the shell material at intervals adjacent to the fold lines, forming apertures in the shell material in substantially centered relation to the skived areas, forming narrow longitudinal slots in the shell web substantially co-extensive with the fold lines and of substantially the same length as the skived areas, advancing a continuous web of cover material and applying it adhesively to a surface of the shell web, slitting the cover material on lines substantially corresponding to the longitudinal slots

above mentioned, forming transverse fold lines, cutting off the combined materials at regular intervals to produce individual box blanks, and folding and securing the individual blanks in box form.

14. A continuous box production method comprising the steps of associating a continuous web of shell material and a continuous web of cover material in facial contact with interposed adhesive, producing longitudinal and transverse fold lines in the materials, producing skived areas on an outward face of the shell material adjacent to the longitudinal fold lines and narrow longitudinal slots alongside the skived areas whereby thin free edges of the shell material are produced corresponding to edges of the shell end wings in the completed blank assemblies, severing the combined materials transversely at regular intervals to produce the individual assemblies, and folding and securing the individual blanks in box form.

15. A method of producing box blanks comprising the steps of forming in a sheet of box shell material longitudinal slots substantially in line with fold lines, applying a sheet of cover material to one face of the shell sheet and securing it adhesively, and severing the cover material substantially centrally of the shell slots to provide cover margins foldable over adjacent shell edges.

16. A method of producing box blanks comprising steps of forming in a sheet of box shell material longitudinal slots substantially in line with fold lines, applying a sheet of cover material to one face of the shell sheet and securing it adhesively, severing the cover material substantially centrally of the shell slots to provide cover margins foldable over adjacent shell edges, and creasing and shaping the blank for folding.

17. A method of producing box blanks, comprising advancing a continuous web of shell material, forming narrow longitudinal slots therein in line with wing-folding lines, applying cover paper to one side of the shell web and over the slots and adhesively securing the cover paper, slitting the cover material overlying the shell slots on lines substantially central of the slot widths, and severing the combined materials transversely at regular intervals to produce individual box blanks.

18. A method of producing box blanks, comprising advancing a continuous web of shell material, forming narrow longitudinal slots therein in line with wing fold lines, applying cover paper to one side of the shell web and over the slots and adhesively securing the cover paper, producing longitudinal and transverse fold lines to define wing formations, slitting the cover material overlying the shell slots on lines substantially central of the slot widths, and severing the com-

bined materials transversely at regular intervals to produce individual box blanks.

19. A method of producing composite box blanks including sheet shell and cover material and having a body section and wings projecting therefrom, said method comprising reducing the thickness of certain of the shell wing margins and slotting the shell material adjacent the zones of reduced thickness to provide free cover margins projecting beyond the shell edges for smooth, flat adhesive application to other portions of the blank when it is formed into a box part.

20. A method of producing box blanks comprising producing wing formations in a sheet of shell material, reducing the thickness of certain of the wing margins, applying sheet cover material to a face of the shell, and cutting the sheet material on lines adjacent the shell wing zones of reduced thickness to provide thin blank edges for smooth, flat adhesive application to other portions of the blank in the complete box part.

21. A method of producing box blanks comprising slotting a sheet of shell material to provide blank wing formations having substantially separated adjacent edges, reducing the thickness of certain of the wing margins adjacent the slots, applying a sheet of cover material to one face of the shell with portions overlying the slots, and severing cover material on lines adjacent the shell edges of reduced thickness to provide free cover margins for adhesive application to other blank surfaces when the blank is formed into a box part.

Signed at New York city in the county of New York and State of New York this 20th day of December A. D. 1922.
